UNITED STATES PATENT OFFICE.

NIEL GRAY, JR., OF OSWEGO, NEW YORK.

PAPER-CUTTING MACHINE.

SPECIFICATION forming part of Letters Patent No. 744,534, dated November 17, 1903.

Application filed November 11, 1901. Renewed August 22, 1903. Serial No. 170,487. (No model.)

To all whom it may concern:

Be it known that I, NIEL GRAY, Jr., a citizen of the United States, residing at Oswego, in the county of Oswego and State of New York, have invented certain new and useful Improvements in Paper-Cutting Machines; and I do declare the following to be a full, clear, and exact description of the invention, such as will enable others skilled in the art to 50 which it appertains to make and use the same.

This invention relates generally to paper-cutting machines, and particularly to improvements in the mechanism for operating the clamp which holds the work while it is being cut; and it has for its object to provide means for bringing the clamp down gently to or upon any height of pile when the clamping is automatic, so as to render the automatic clamping as near like hand-clamping 20 as is possible in machines which are run at the highest practicable speeds.

Also it has for its further object to compress the pile of paper slightly by means of a single-piece clamp before the automatic pressure is applied, so as to force out or expel all the air from between the sheets constituting the pile, and thus diminish the tendency of the sheets to slide on each other and also to render the action of the system of 25 gears and of the clamp smooth, so that the automatic pressure mechanism will have full opportunity to exercise its full power in clamping the work, and as a still further object to secure economy in time when cutting low piles of uniform height, either automatically 30 or by hand, by stopping the clamp at a point slightly above the pile in order to reduce the distance it must travel to reach the pile; and the invention consists in the parts and combinations of parts hereinafter described and claimed.

In the accompanying drawings, forming a part of this specification, Figure 1 is a side elevation of a paper-cutting machine with the framework at one side partly broken away, showing my invention in operative position thereon; Fig. 1^a, an enlarged detail view, in vertical section, of means for automatically raising the clamp; Fig. 2, an enlarged detail 45 plan view of my device; Fig. 3, an enlarged detail side elevation of the same; Fig. 4, an enlarged detail section of the bell-crank le-

ver on the line 5 5, Fig. 5; Fig. 5, a side elevation of said bell-crank lever; Fig. 6, an enlarged detail plan view of the gear-segment; Fig. 7, a detail side elevation of the fiber ring; Fig. 8, a detail side elevation of the friction-ring; Fig. 9, an enlarged plan view of the cap-piece of the frame with my stop device in position thereon; Fig. 10, an enlarged front view of the upper part of the frame with the clamp in position; Fig. 11, a detail view of an adjustable stop-pin; and Fig. 12, a vertical section on the line 12 12, Fig. 10.

Similar letters refer to similar parts throughout all the views.

Referring to the drawings, A represents the frame of the machine, and B the bed or table upon which the paper rests while being 70 adjusted and cut. A clamp C, made of a single piece or bar, is arranged to slide in ways in the uprights D of the frame and is connected at each end to straps E, which carry the toothed racks F at their lower 75 ends.

At the front of the machine the crank-shaft G has its bearings in the frame and is to be connected, as is usual, by rods (not shown) to the ends of the knife-stock m, whereby the 80 knife is caused to make one complete stroke—i. e., down and up—at each revolution of the crank-shaft.

The parts hereinbefore described may be of the usual or any desired construction.

At one end of the crank-shaft G an eccentric-disk H is mounted, around which is loosely clamped by the bolts a a strap I, from which an arm J extends, as shown. At a point at the junction of the arm J and strap 90 I a cup K, having a bottom outlet leading between the strap and the eccentric-disk, is formed for the purpose of supplying a lubricant to said parts. A cap or cover L excludes 95 dust.

The outer or free end of the arm J is connected to the end of an arm M, which projects from the periphery of a split ring or rim N, (see Fig. 8,) surrounding and adjustably clamped on a split fiber ring or rim O. (See Fig. 7.) The fiber ring O is arranged on the hub b of a bell-crank lever, (see Figs. 4 and 5,) which is loosely mounted on a shaft P, having its bearings in extensions from the

frame. The hub *b* is provided with the arms or levers *Q* and *R*, one of which, *Q*, as indicated in dotted lines, Figs. 1 and 3, is adapted to engage a lateral projection *c* on the side 5 of a segment-gear *S*, which is also loosely mounted on the shaft *P*, the teeth of said segment meshing with a pinion *T*, mounted on the clamp-shaft *U* and meshing with one of the racks *F*, while a similar pinion (not 10 shown) is mounted near the opposite end of said shaft *U* and engages the other rack.

The action of the above-described mechanism is as follows: When the machine is started from the position shown in Figs. 1 and 3, 15 the crank-shaft *G* revolves in the direction of the arrow and through the eccentric and strap pulls the friction-ring *N* through its arm *M* slowly when it first starts and attaining its maximum speed when said shaft *G* has 20 gone through or made one-quarter revolution, when the speed gently decreases again until the shaft has made or completed one-half revolution or another quarter-revolution. The friction-ring *N*, binding through the fiber 25 ring *O* upon the hub *b* of the bell-crank lever, rotates said hub in the direction of the arrow. This movement causes the end of arm or lever *Q* to swing upwardly, and through its engagement with projection *c* rotates the 30 segment *S* about the shaft *P*, and at the same time the segment rotates the pinion *T* and clamp-shaft *U*, thereby causing the racks *F* to lower the clamp to the paper. As the clamp reaches the paper, it is pressed gently, 35 but with gradually-increasing power, upon the pile until the resistance of the latter overcomes the frictional contact between the split ring *N* and the fiber ring *O*, when the ring *N* is forced to swing through its arc, sliding 40 on ring *O* until the crank-shaft *G* has passed its half-revolution point, at which time the eccentric on said shaft reverses the direction of motion of the ring *N*, and thus carries the end of arm *Q* away from the projection *c* on 45 segment *S*, so that the clamp is free to be returned to its topmost position. Any suitable means may be employed to return the clamp to its raised position—such, for instance, as shown in Fig. 1^a—in which *B'* represents pockets formed in the side pieces of the frame 50 near the front of the same and opposite each other, and a slot *C'* is formed in the contiguous faces of the pockets in which the strap or rack bars *D'* work and through which the 55 arms *E'* of brackets *F'*, secured to the top of the clamp at each end thereof, extend. Through the ends of the arms *E'* rods *G'* extend to and through caps *H'* and are held in place by nuts run on the reduced and threaded 60 ends of the rods, and a hand-wheel is provided for each rod, whereby it may be adjusted to increase or decrease the tension of the springs *I'*, surrounding the rods within the pockets and bearing against arms *E'* of 65 the brackets, as fully described in my United States Patent numbered 680,655, dated August 13, 1901.

If the clamp had come down flush upon the table without a pile upon it, the relative positions of the friction-ring *N* and the arm or lever *R* would not be changed, and the clamp would be free to return to its topmost position again without the projection *c* striking the end of arm or lever *Q*; but with a pile of paper interposed between the clamp and the table the slipping of the friction-ring *N* would change the relative positions of said ring and the arm or lever, and in order to return the arm or lever *R* to its previous relative position with ring *N*, I provide a stop device for 80 holding the bell-crank lever stationary during the period the ring *N* is being swung through its arc after the resistance has become sufficient to overcome the friction. This device in this instance consists of a pin 85 *V*, adjustably secured in a bracket *W*, projecting from the frame and arranged in position to be engaged by the end of said arm or lever *R*, and thus limit its farther rearward movement or swing. (See Fig. 1.) 90 Further, as a means of relieving the arms or levers *Q* and *R* of the effects of blows to which they may be subjected by reason of the return of the clamp to its top position I have devised a means for arresting the clamp 95 *C* at any desired height in its upward movement. This device is best shown in Figs. 9, 10, and 12 of the drawings, and in which *d* represents the cap-piece of the frame, and *e* short shafts, which are journaled vertically 100 near each end of said cap-piece. On the upper end of one of the shafts *e* a handle *f* is secured, and on the lower ends of the said shafts bell-crank levers are secured, the long arms *g* of which are connected by a link *h*, 105 while the short arms carry the downwardly-projecting pins *i*, whereby the said pins may be swung in or out under said cap-piece and into or out of the path of the clamp. In the drawings the pins *i* are shown in their out 110 position or to one side and out of the line traveled by the clamp, so that the latter may be raised to the top of the frame; but if the pins are swung back and over or in line with the clamp, which may be readily done by 115 turning the handle *f* in the proper direction, the upward movement of the clamp will be arrested by said pins. In order to provide for arresting the clamp at different heights, the pins are preferably made adjustable as 120 to length, and in Fig. 11 I have shown one way in which this may be accomplished and in which figure *i'* represents the pin having its lower end screw-threaded and adapted to enter a screw-threaded socket formed in a cap 125 or head *j*. Thus the head may be adjusted up or down on the screw and secured in its adjusted position by a nut *k*, thereby practically lengthening or shortening the pin, as desired, and enabling the clamp to be arrested in its upward movement at any desired point within the limits of adjustment of the pin and its head. To obtain the best result 130 on any height of pile of paper—*i. e.*, to make

the clamp descend as gently as possible upon the pile—it is necessary to adjust the pin *i*' and the stop-pin *V* with relation to each other so that the end of arm *Q* just clears the 5 projection *c* of the segment-gear *S* when the arm *R* is in contact with the stop-pin *V*.

The clamp being in one piece, and therefore having but one set of ways, is more durable and can be depended upon to hold the 10 work accurately longer than when the clamp is divided into two or more parts—one for marking or gaging the work and the other for compressing it. For nearly all purposes one stop device which will allow the full 15 travel of the clamp and another which will stop the clamp one-half way up will secure a gentle enough action to obtain good results; but the adjustable feature of the pins *i*' for the clamp and the stop-pin *V* for the 20 arm *R* permits of the best results being obtained in any case, no matter what height pile is being cut.

The arrangement of the lever *h* on cap-piece *d* is not absolutely necessary except a 25 stop of some such kind is desirable from a mechanical standpoint, so as to relieve the blow this system would give the arm *Q* in case said arm was alone used to check the clamp in its upward course.

30 Having thus described my invention, what I claim as new, and desire to secure by Letters Patent, is—

1. In a paper-cutting machine, the combination, with a crank-shaft and a clamp, of a 35 clamp-shaft in operative connection with the clamp, an intermediate supporting-shaft, an arm or lever loosely mounted on said supporting-shaft, a friction device secured to said arm or lever to impart motion thereto, 40 means operated by said arm or lever for rotating said clamp-shaft, means connecting the crank-shaft and friction device for operating the latter, and a stop device for arresting the clamp at any desired point in its up- 45 ward movement.

2. In a paper-cutting machine, the combination with a clamp, of a crank-shaft, a clamp-shaft in operative connection with said clamp, a friction device for operating said clamp- 50 shaft, and means, connecting said friction device and crank-shaft, for imparting a gradually-increasing speed to said friction device during the first part of the revolution of said crank-shaft and a gradually-decreasing speed

during the latter part of its revolution, where- 55 by the clamp is brought down gently to its work.

3. In a paper-cutting machine, the combination, with a clamp, of a clamp-shaft, a friction device, a crank-shaft, an eccentric 60 mounted on said crank-shaft and connected to said friction device, means for connecting said friction device to said clamp-shaft to rotate the latter, and a stop device for limiting the upward motion of said clamp. 65

4. In a paper-cutting machine, the combination, with a clamp and racks connected therewith, of a clamp-shaft having pinions meshing with said racks, a segment-gear engaging one of said pinions, a bell-crank lever 70 for operating said segment-gear, a crank-shaft, and a friction device operated from said crank-shaft for swinging said bell-crank lever.

5. In a paper-cutting machine, the combination, with a clamp and racks connected therewith, of a clamp-shaft having pinions meshing with said racks, a segment-gear engaging one of said pinions, a bell-crank lever 75 for operating said segment, a friction device 80 for operating said bell-crank lever, a stop for limiting the throw of said bell-crank lever, and a crank-shaft for operating said friction device.

6. In a paper-cutting machine, the combination, with a clamp and racks connected therewith, of a clamp-shaft, pinions mounted on said shaft to engage said racks, a segment-gear meshing with one of said pinions, an arm for imparting motion to said segment, a 90 friction device for operating said arm, and a crank-shaft for operating said friction device.

7. In a paper-cutting machine, the combination, with a clamp, and means for arresting the upward movement of the clamp at 95 any desired point, of a bell-crank lever for operating said clamp in one direction, a friction device for operating said bell-crank lever, a crank-shaft for operating said friction device, and means for arresting the return 100 movement of said bell-crank lever.

In testimony whereof I affix my signature in presence of two witnesses.

NIEL GRAY, JR.
